UNITED STATES PATENT OFFICE.

HERMAN L. BEAL, OF BROOKLINE, MASSACHUSETTS.

RUBBER HEEL.

Application filed June 17, 1918. Serial No. 240,375.

To all whom it may concern:

Be it known that I, HERMAN L. BEAL, a citizen of the United States, residing at Brookline, in the county of Norfolk and 5 State of Massachusetts, have invented certain new and useful Improvements in Rubber Heels; and I do hereby declare the following to be a full, clear, and exact description of the invention, such as will enable 10 others skilled in the art to which it appertains to make and use the same.

The present invention relates to an improvement in rubber heels.

Concavo-convex heels such as shown in 15 the Nerger Patent No. 661,122 commend themselves by reason of the close union which they secure between their edges and the edges of the heels to which they are applied. The heels of the Tufford Patent Re. 20 No. 14,049 commend themselves to the user for the same reason, but they are liable to bulge between the nails. The latter, however, are attached by nails which pass through washers embedded in the heels, and 25 the former by screws which pass through holes in a central plate. Owing to the distortion of concavo-convex heels incident to attaching them to the shoe it is more or less difficult to apply these heels securely to the 30 shoe. The loosening of one of the nails of Tufford permits the adjacent portion of the heel to bulge outwardly; the use of separate screws as in Nerger requires more time and 35 skill to attach the heel. Hooper in his Patent No. 1,236,174 proposed to embed a flat plate in his concavo-convex heel, and to provide it with protruding nails by which the heel could quickly be attached to a shoe.

Hooper's plate, however, was stiff and flat, 40 and when the heel was flattened upon the shoe heel it caused the bending of the heel body to be localized at the edges of the plate, with the result that the compression of the material on the convex side of the 45 heel was correspondingly localized and a bulge or ridge on the tread surface resulted therefrom. It is obviously desirable to eliminate this bulge or ridge, and to this end the curvature of the heel should be continuous throughout, so that there will be no 50 localized bending of the heel. As an incident to this end to contribute to the exclusion of localized bending, the heel in its preferred form contemplates the use of a 55 nail plate curved to correspond to the curvature of the heel, and made of flexible mate-

rial so as to bend with the heel when it is flattened out on the shoe heel. The present invention, therefore, contemplates a rubber heel of continuous curvature preferably provided with a nail plate curved to correspond with the curvature of the heel and made of flexible material so as to bend with the heel as the latter is applied to the shoe, and having rigidly attached nails so that when the 60 heel is nailed on the shoe heel, the heel and plate bend together and the bending of the heel is extended throughout the whole body of the heel.

Another feature of the present invention 70 consists in making the nails slightly divergent. This feature of construction contributes to the secure attaching of the heel to the shoe for two reasons, first, because the nails diverge in the body of the heel, thereby 75 tending to flatten the heel on the shoe, and, second, because since they diverge they have increased holding capacity for securing the heel to the shoe.

The present invention consists in the rubber heel hereinafter described and particularly defined in the claims.

In the accompanying drawings Figure 1 is a perspective of the preferred form of the heel embodying the improvements of the 85 present invention; Fig. 2 is a plan of the heel shown in Fig. 1, showing particularly the location of the nail-holding plate; Fig. 3 is a transverse section taken on the line 3—3 of Fig. 2 looking in the direction of the 90 arrow; Fig. 4 is a transverse section showing the rubber heel attached to the heel of a boot or shoe; and Fig. 5 is a longitudinal section taken along the line 5—5 of Fig. 2 looking in the direction of the arrow. 95

The heel shown in the accompanying drawings is a concavo-convex heel of the general shape shown in the Nerger patent, that is to say, the heel comprises a body portion of which the upper side edges 10 and 100 the upper rear edge 11 lie in one plane whereas the upper breast edge 12 is depressed below the plane in which the upper side and rear edges lie. The upper face or surface 14 of the heel constitutes its attaching face, this being the face which is applied to the bottom of the leather heel of the boot or shoe to which the rubber heel is attached. This attaching face 14 curves upwardly laterally from its bottom 15 to the upper side 110 edges 10. The bottom 15, together with the adjacent lateral part of the attaching face,

lies parallel with the plane of the upper side edges 10 to substantially the point 16 (Fig. 5) which may conveniently be two-thirds or thereabouts the length of the heel. From 5 this point 16 to the rear edge 11 of the heel, the attaching face 14 curves rearwardly and upwardly. The bottom side edges 18 of the rubber heel and the bottom rear edge 19 all lie in a plane parallel to the plane in which 10 the upper side edges 10 and rear edge 11 lie. The bottom breast edge 20 curves conformably to the upper breast edge 12 and the bottom face or tread surface 22 of the heel is curved correspondingly to the curvature 15 of the attaching face 14.

The nail-holding plate corresponds in curvature to the curvature of the part of the heel in which the plate is embedded. So in the illustrated embodiment of the invention the nail-holding plate 24 is laterally curved and longitudinally straight because that part of the heel in which the plate is embedded is laterally curved and longitudinally straight. The plate, therefore, lies parallel with both the attaching face 14 and the tread surface 22.

The nail-holding plate 24 lies much nearer the attaching face 14 of the heel than it does the tread face or surface 22 to permit 30 the heel to wear away substantially two-thirds of its thickness before exposing the nail holding plate 24.

Fixed uprightly in this nail-holding plate 24 are the nails 25 which protrude from the attaching face 14 of the heel and are adapted to be driven into the leather heel of the boot or shoe. These nails are arranged divergently. The divergence is such that the distance between two nail points is equal to 40 the distance between their shanks at the surface of the heel measured along such surface.

The heel is applied to the leather heel of the boot or shoe by placing the shoe on a metal-bottomed last or jack, supporting the rubber heel in the proper position over the heel of the shoe, and hammering on the bottom of the heel so as thereby to drive the nails into the heel of the shoe, and, if 50 they are long enough, to clinch them against the last or jack. In driving the nails home the heel is flattened out on the bottom of the shoe heel, the nails diverging somewhat more as the heel approaches its final position. Not only do the nails by reason of 55 their divergence hold the heel more securely on the shoe, but they thereby tend to bend the heel and flatten it out against the shoe heel so that the entire attaching face of the heel will tightly hug the heel of the shoe, not only throughout the marginal portion, but also throughout the central portion.

The present invention may be embodied in any type of concavo-convex heel whether

spherically concavo-convex like the heel of 65 Ferguson Patent No. 638,228 and the Tufford patent above referred to or of the Nering shape, or otherwise. The nail-holding plate may be of any desired shape or form preferably corresponding in curvature to the 70 curvature of the part of the heel in which the plate is embedded. While the divergent nail feature of the invention is more useful when employed in connection with nail-holding means consisting of a plate, it is apparent 75 that it might be used in connection with any suitable nail-holding means to obtain the more secure attachment of a heel to a shoe.

Having thus described the invention what is claimed is:—

1. A rubber heel comprising a body portion having a continuously curved concave attaching face and a correspondingly curved convex tread face, a flexible nail-holding plate embedded in the central portion of the 85 heel corresponding in shape to the curvature of the part of the heel in which the plate is embedded, and a plurality of divergent attaching nails fixed in the plate and protruding from the attaching face. 90

2. A rubber heel of continuously curved concavo-convex form throughout, a flexible curved metallic nail holding plate embedded in the central portion of the heel shaped to correspond to the curvature of the part of 95 the heel in which it is embedded, and a plurality of attaching nails rigidly fixed in the plate and protruding from the attaching face of the heel, the flexibility of the plate operating to permit the heel to be flattened 100 against the shoe heel without localized bending in the plate when the different nails encounter different degrees of resistance in being driven into the shoe heel.

3. A rubber heel comprising a body portion having a concave attaching face, nail-holding means embedded in the heel, and a plurality of divergent attaching nails fixed in the nail-holding means and protruding from the attaching face. 110

4. A rubber heel comprising a normally concavo convex body portion, a nail holding plate curved in conformity with the curvature of the heel and embedded in the body portion, and a plurality of divergent attaching nails fixed in the plate and protruding from the attaching face of the heel. 115

5. A rubber heel comprising a normally concavo convex body portion, a nail holding plate curved in conformity with the curvature of the body portion and embedded in the body portion, and a plurality of divergent attaching nails fixed in the plate and having their points separated a distance substantially equal to the distance between 120 their shanks at the attaching surface of the heel measured along such surface. 125
